BAND-FILTER COUPLING CIRCUIT FOR
TELEVISION AMPLIFIERS

Kurt Schlesinger, Berlin, Germany, assignor, by
mesne assignments, to Loewe Radio, Inc., a cor-
poration of New York

Application April 12, 1937, Serial No. 136,412
In Germany April 16, 1936

2 Claims. (Cl. 179—171)

The present invention relates to band-filter circuits for coupling amplifier arrangements used for amplifying wide frequency-bands as they are used for television purposes.

In intermediate-frequency amplifiers for television superheterodynes and transmission amplifiers for television purposes coupling circuits are known which consist of a pair of coils, each single coil being tuned per se to the unmodulated carrier wave and the two coils being so tightly coupled together that the frequency-curve of this circuit is sufficiently wide to cover the television frequency band. It is known that band-filter coils of this nature such, for example, as already described in the application Ser. No. 24,901 of June 4, 1935, Patent No. 2,131,193, issued Sept. 27th, 1938, drop off sharply only in the short-wave range whilst in the long-wave range they strive to reach an extreme value in the quality of transformation, which is not zero. There is required, however, in the present television art a transformation which drops off equally towards both sides.

In the accompanying drawing embodiments of band-filter circuits in accordance with the invention are shown.

Fig. 1 shows a band-filter circuit for transmitting a wide frequency band. The curve of the frequency range transmitted by this arrangement has a sharply dropping off at both sides of the frequency band.

Fig. 2 shows the curve of the frequency band transmitted by the circuit shown in Fig. 1.

Fig. 3 shows a further embodiment of the band-filter circuit according to the invention.

In Fig. 1 a first embodiment of a transformation of this character is shown, which avoids the stated disadvantage of the purely inductive system. The primary coil 1 is not directly connected to the anode of the first tube 3, but is coupled by way of a condenser 4. The tube 3 itself acts in direct fashion on an ohmic resistance 5. The condenser 4 and the primary inductance 1 are so tuned in relation to one another that series resonance occurs on a wave adjustable by condenser 4, which wave has a frequency lying in that end of the side-band frequency spectrum which contains the higher frequencies (short wave end).

On the other hand the secondary inductance 2 with the accompanying inherent and grid capacity 6 is tuned to a wave which has a frequency lying in the long-wave range of the spectrum or even beyond the long-wave end. There then occurs the effect to be seen from Fig. 2.

The curve *a* represents the resistance amplification occurring at the resistance 5. As well known, this decreases after short waves in proportion to the wave-length owing to the accompanying capacities.

The curve *b* represents the potential across the primary coil 1. This has a resonance maximum at 7, which is adjusted by series resonance between 4 and 1. The magnetic field is represented by a curve *c*, and fades less quickly than the potential in the long-wave range of the frequency spectrum. The curve *d* shows the potential across the secondary coil excited by a constant field. Owing to the natural resonance this curve possesses a resonance peak at 8, and towards the lower frequencies it descends in proportion to the frequency.

The final curve *e* results from the superimposing of the coupling field curve *c* and the frequency curve *d* of the secondary circuit. This final curve descends in the short-wave range of the frequency spectrum in similar fashion to the field curve *c*. In the long-wave range, however, it drops very considerably owing to the effect of the coupling condenser 4 according to the invention. The desired result is a transformation curve which is limited sharply towards both ends.

To avoid plastic effects at the image screen both coils must be damped at least aperiodically by means of resistances 9 and 10. The resistance 5 cannot be made larger than it is determined by the shunted inherent capacities.

Practical dimensions are approximately as follows:

Television image 400 lines, 25 images per second	35
Width of side band, twice 1.6	
Resistance 5, 2,500 ohms.	
Condenser 4=0.2·10 ⁻⁴ —0.6·10 ⁻⁴ μf	
Resistance 9, 7,500 ohms	40
Resistance 10, 5,000 ohms	
Coil 1 having resonance effect at approximately 60 metre wavelength	
Coil 2 having resonance effect at approximately 120 metre wavelength	45
Carrier wave, 70 metres	
Extreme side waves, 50 metres and 150 metres	

In view of the above explanation of Fig. 3, in which a purely inductive band filter with the coils 1 and 2 is caused to perform a quicker drop in the long-wave range by means of RC members 11, 12 and 13, 14, will be readily understood. In this case the tube 3 is also coupled by ohmic resistance 15.

The condenser 11 connected between the primary and the anode of the tube 3 corresponds to condenser 4 in Fig. 1. Further an additional condenser 13 is arranged between the secondary and the grid of the succeeding tube. This condenser is thus dimensioned as to effect in combination with the natural frequency of the secondary a sharp cutting-off of that end of the broad television frequency band which extends 10 towards the low frequency values.

There is common to both of said circuit systems shown in Figs. 1 and 3 a combination of capacitative and inductive coupling, the capacitative couplings producing series resonance in the 15 short-wave range and the inductive couplings resonance in the long-wave range.

I claim:

1. In a television amplifier arrangement, more particularly for intermediate-frequency amplifier systems, the use of a combined inductive and capacitative coupling circuit between two succeeding tubes having at least a cathode, a grid and a plate, comprising a transformer, damping resistances connected in parallel to the primary and secondary of said transformer, and a variable 25 condenser, the primary of said transformer being connected to the plate of the preceding tube via said variable condenser in serial connection, said variable condenser being so adjusted

as to fall in resonance with said primary at the high-frequency end of the frequency band to be transmitted, the secondary being connected between grid and cathode of the associated tube and tuned with the associated inherent capacities to the low-frequency end of the frequency band to be transmitted. 5

2. In a television amplifier arrangement, more particularly for intermediate-frequency amplifier systems, the use of a combined inductive and capacitative coupling circuit between two succeeding tubes having at least a cathode, a grid and a plate, comprising a transformer, damping resistances connected in parallel to the primary and secondary of said transformer, and a variable 15 condenser, the primary of said transformer being connected to the plate of the preceding tube via said variable condenser in serial connection, said variable condenser being so adjusted as to fall in resonance with said primary at the high-frequency end of the frequency band to be transmitted, the secondary being connected between grid and cathode of the associated tube and tuned with the associated inherent capacities to the low-frequency end of the frequency band to 20 be transmitted, a condenser being inserted between said secondary and the grid of said associated tube. 25
